UNITED STATES PATENT OFFICE.

WELLINGTON R. HANES, OF CHICAGO, ILLINOIS.

GARMENT.

1,153,909.

Specification of Letters Patent. Patented Sept. 21, 1915.

Application filed March 15, 1915. Serial No. 14,325.

To all whom it may concern:

Be it known that I, WELLINGTON R. HANES, a citizen of the United States, residing at Chicago, in the county of Cook and 5 State of Illinois, have invented certain new and useful Improvements in Garments, of which the following is a specification.

The object of this invention is to provide a garment which can be readily applied to 10 protect the clothes of the wearer from dirt and damage.

It has been common practice heretofore for men to use aprons and overalls to protect their clothes while at work and while these 15 answer the purpose to a certain extent they are objectionable in many respects. Aprons can not safely be worn near machinery and do not furnish sufficient protection to the clothes; overalls furnish sufficient protection 20 but they can not be readily put on and taken off over the shoes and pants and are uncomfortably hot when worn over the pants in warm weather. There are many times when a man is unexpectedly called upon to do 25 some work which is very apt to result in damage to his clothes, such as work on an automobile, when an apron would not furnish sufficient protection and it would be inconvenient to put on overalls.

30 The object of my invention is to provide a garment of simple construction which can be readily put on and taken off, which will furnish all the protection that is required for the clothes of the wearer and which can 35 be safely worn around machinery without danger of accident.

In the accompanying drawings illustrating the invention Figure 1 is a front elevation of the garment as it appears in actual 40 use on a man; Fig. 2 is a rear elevation of Fig. 1; Fig. 3 is a perspective view showing the garment from the rear.

45 Referring to the drawings, the garment comprises leg members 4, 4 which are sewed together along the line 5 and are also sewed at the waist line 6 to the apron 7. I make the garment in sizes and prefer and intend that the leg members shall extend down far enough to cover the pants of the wearer 50 throughout their length and that the apron shall extend up far enough upon the chest of the wearer to furnish ample protection for his clothes. The leg members are of sufficient width to protect the wearer's pants not

only at the front, as shown in Fig. 1, but also 55 at the sides, as shown in Fig. 2, and in order to hold these leg members in position upon the wearer, as shown in the drawings, I provide each member with a plurality of straps which are preferably fastened securely at 60 one end to the outer edge of the leg member and are adapted to be detachably fastened to the inner edge of the leg member. I have found it convenient to provide on each leg member a strap 8 adjacent to the crotch, an- 65 other strap 9 at the knee and another strap 10 at the ankle, each of these straps being fastened by rivets or other suitable means at 8', 9' and 10', respectively, to the outer edge of the leg member. The free end of each of 70 these straps is adapted to be engaged with the inner edge of the leg member, preferably by suitable snap fasteners 8", 9" and 10". The straps 9 and 10 are preferably arranged to extend straight across the wearer's leg at 75 the back thereof and the fastening device 8" for the strap 8 is located as close to the crotch 11 of the garment as will be convenient for fastening and unfastening this strap, but the outer end of this strap 8 is prefer- 80 ably fastened to the outer edge of the leg member farther up the leg member than the fastening device 8" so that the strap 8 will extend diagonally across the back of the wearer's leg and tend to pull the garment 85 snugly over the hip of the wearer. The leg members are shaped at the crotch so that the garment will project in between the legs of the wearer sufficiently to provide ample protection for the pants at the crotch. I also 90 provide a waist band 12 and a neck band 13 for fastening the garment around the waist and supporting the apron from the neck of the wearer.

95 My invention provides a garment which can be quickly and easily put on and taken off and which furnishes sufficient protection to the wearer's clothes for all ordinary purposes. It is particularly adapted and suitable for use in emergencies in connection 100 with automobiles where it is often desirable to have a garment which can be readily put on to protect the wearer's clothes while replacing a tire or making other repairs on the machine. This garment can be readily applied over the clothes of the wearer and it is 105 not necessary for the wearer to sit down in order to put the garment on or take it off.

While the garment is particularly adapted for emergency use it is also suitable for regular use by mechanics in their daily work since it will furnish sufficient protection to 5 the clothes in many avocations.

I claim:

A garment of the character described, comprising a pair of members connected at a medial line at the front from approximately 10 the waist portion to and under the crotch, said members having leg portions adapted to partially surround the front portions of the legs of the wearer and having an inwardly projecting portion at the junction 15 of the leg portions to fit under the

crotch, an adjustable fastening device at or about the waist portion thereof, and means for securing the leg portions in place at various points throughout the length thereof, including a pair of straps extending from 20 the outer edges of the members diagonally downward to the inner edges thereof to draw the outer edges of the members over the hips of the wearer and to assist in holding in place the crotch portion of the garment.

WELLINGTON R. HANES.
